DESIGN FOR A COIN PURSE

Harry P. Behrman, Kew Gardens, N. Y.

Application December 30, 1944, Serial No. 117,178

Term of patent 7 years

(Cl. D87—3)

To all whom it may concern:

Be it known that I, Harry P. Behrman, a citizen of the United States, residing at Kew Gardens, in the county of Queens and State of New York, have invented a new, original, and ornamental Design for a Coin Purse, of which the following is a specification, reference being had to the accompanying drawing, forming a part thereof.

side of the coin purse, showing my new design, and

Figure 2 is a perspective view of the inside thereof.

The side of the coin purse not shown in the drawing is substantially plain.

I claim:

The ornamental design for a coin purse, substantially as shown and described.

HARRY P. BEHRMAN.
